(57) **CLAIM**

The ornamental design for an ammunition rack, as shown and described.

DESCRIPTION

The invention described here may be made, used and licensed by and for the U.S. Government for U.S. Governmental purposes.

FIG. 1 is a front, downward looking isometric view of the ammunition rack;

FIG. 2 is a front elevation view of the ammunition rack;

FIG. 3 is a right side elevation view of the ammunition rack;

FIG. 4 is a top plan view of the ammunition rack; and,

FIG. 5 is a bottom plan view of the ammunition rack.

Views are orthogonal projections unless otherwise noted. The various views are not necessarily to scale in order to better illustrate the design.
